UNITED STATES PATENT OFFICE.

HARRY O. RUGH, OF SANDWICH, ILLINOIS, ASSIGNOR TO SANDWICH ELECTRIC COMPANY, OF CHICAGO, ILLINOIS, A CORPORATION OF ILLINOIS.

SIGNALING AND TELEPHONE SYSTEM.

1,016,036.

Specification of Letters Patent.

Patented Jan. 30, 1912.

Original application filed June 26, 1908, Serial No. 440,571. Divided and this application filed February 15, 1910. Serial No. 543,969.

To all whom it may concern:

Be it known that I, HARRY O. RUGH, citizen of the United States, residing at Sandwich, in the county of Dekalb and State of Illinois, have invented a certain new and useful Improvement in Signaling and Telephone Systems, of which the following is a full, clear, concise, and exact description, reference being had to the accompanying 10 drawings, forming a part of this specification.

My invention relates to signaling and telephone systems, and is a divisional application of application, Serial No. 440,571, filed 15 June 26, 1908.

In the application of which this is a division, I show and claim a plurality of circuits which are adapted for telephone and telegraph use, and in which one circuit is 20 adapted to carry selective signaling appliances, in connection with telegraphic appliances in connection with local or block telephone circuits, and in which the other circuit is adapted to be clear and to be provided with telephonic appliances, which are brought into use when the selective call is brought over the first-aforesaid circuit.

In the present application I set forth and claim two circuits, one of which is adapted 30 for telephonic transmission, so as to provide a clear circuit for this work, and the other circuit of which is to be provided with instrumentalities having selective calling features thereon, so as to call a station, and 35 the telephone on the other circuit may be used, and in which the circuit carrying the selective calling devices is at the same time enabled to carry on block or inter-station telephone service.

40 I will describe my invention more in detail by reference to the accompanying drawing illustrating the preferred embodiment thereof, in which—

Figure 1 illustrates diagrammatically the 45 circuits, and Fig. 2 shows in detail the selective calling mechanism.

Referring more particularly to Fig. 1, I show a circuit consisting of the line wire 1, grounded at its extremities, and a second circuit, 2, likewise grounded at its extremities through suitable instrumentalities, as 50 will hereinafter appear. I have shown the central station A; and substations B, C and D, as illustrative of a plurality of stations.

The object of my invention is to provide 55 a good telephonic circuit, and this is the circuit consisting of the line wire 1, which goes through all of the stations, and which is provided in this particular instance at each station with a jack 3, which jack is connected for use with a plug 4, which plug has connected to it, in a metallic circuit, the receiver 5, induction coil 6, transmitter 7, battery 8, condenser 9, generator 10, and the switch-hook 11. Each jack 3 is grounded 60 as shown, because in this application the conductor 1 is illustrated as being grounded, although, of course, the grounded feature forms no portion of the invention, it being used merely for the sake of clearness. At 65 the despatcher's station, A, the telephonic appliances are similar, with the exception that the generator 10 is omitted.

At the central station there are provided two generators, preferably 12 and 13, designed to deliver positive and negative current, which generators, as shown, are grounded and controlled by two keys, 14 and 15, so that positive and negative current may be sent over the line circuit 2, 70 with which these aforesaid appliances are associated. These keys are used to operate selective calling devices 16 at the various substations, which selective calling appliances are shown in detail in Fig. 2, wherein 75 a polar relay 17 is shown serially included with a line wire 2, and, depending upon the polarity of the current, contacts with either contact point, 18 or 19, the spring 20 holding the armature normally away from both 80 contacts. A battery 21 is connected to the central portion of the armature 22. When impulses are sent over the line wire, so that the contact 18 is included in circuit, magnet 23 operates to step up the impulse mechanism 24, which, when wholly stepped up, 85 closes circuit with the spring 25, thereby closing circuit through the battery 26 and relay 27, to actuate the signal 28 by means of the battery 29.

100 It will of course be understood that the arms 30 are placed at different angular positions in the different stations, so that different stations respond to different numbers of stepping-up impulses. When the 105 signal calling operation is complete, a negative impulse is sent over the line, so that the armature 22 contacts with a contact 19,

to close circuit through the magnet 31, thereby to release the locking pawl 32 and the step-up arm 33 to allow the element 24 to return to its normal or zero position, a stop 5 34 being provided for this purpose.

It will thus be seen that through the instrumentalities thus far described, central station A can call any of the substations, and when so called, the substation operator 10 has instructions to insert plug 4 into jack 3, and to talk to the train despatcher over the clear circuit 1, it being of the utmost importance that a clear train despatcher's circuit be at all times maintained. I 15 provide further instrumentalities so that the interstation telephonic service can be carried on, for instance, between stations B and C, and if sufficient telephonic appliances are at hand, likewise between stations 20 B and A; and to this end the central station A has a jack 35, which finds its mate in the jack 35 at the station B, and stations B and C have jacks 36, which are adapted for conjoint use, and stations C and D have 25 jacks 37 which are adapted for conjoint use. The jacks 35, 36 and 37 of course accommodate the plugs 4. At each station there are shown means for controlling the inter-station telephonic service, and this is done in 30 this particular instance through the agency of the quadrilateral resistances, consisting of the two resistance coils 38, and the two impedance coils 39, which are shown throughout all of the stations, each station 35 having two quadrilateral resistances. Condensers 40 are also provided to conduct the talking currents to ground. Magneto bells 41 are provided at each of the substations to respond to the generators 10, when called 40 for interstation service. The interstation talking circuit, for instance, between stations B and C, will be as follows: from the right hand condenser 40 of stations B, through the resistance 38, through jack 45 36, and consequently, the telephonic substation apparatus, thence through the second resistance 38, over the line wire 2, between these two stations, thence through the resistance 38 of the left hand quadrilateral 50 resistance of station C, thence through the jack 36 and its associated telephonic appliances, through the second left hand resistance 38 of station C, through the left hand condenser 40, of that station to ground. 55 These quadrilateral resistances or plates, it will be seen, prevent telephonic currents from passing beyond the circuit just outlined, at least, in sufficient measure to prevent commercial disturbance, the reason 60 being that no telephonic currents can pass serially through all the branches of said quadrilateral resistance, as will be apparent to those skilled in the art. Thus, telephonic currents passing over the circuits just outlined 65 will be stopped from going farther by

the left-hand quadrilateral resistance of the station B, and the right hand quadrilateral resistance of the station C. The direct current impulses, of course, can pass through these resistances, as they are not sufficiently rapid to be largely deflected. In this connection, it might be stated that relay 27, of course, is a slow-acting relay. I thus attain a clear despatcher's circuit by loading the circuit 2 with the selective calling features, 70 and yet, at the same time, secure inter-station block telephone service, if so desired, over the circuit 2, the circuit 1 being for the exclusive use of the despatcher.

While I have herein shown and particularly described the preferred embodiment of my invention, I do not desire to limit myself to the precise construction and arrangement herein set forth, but

Having thus described the salient features 85 of my invention, what I claim as new and desire to secure by Letters Patent is:

1. A system of the character described comprising a central station and a plurality of substations, a telephone set at each station, a line circuit uniting said stations, to which said telephones are adapted for connection, a second line circuit uniting all of said stations, a selective signal-receiving device including a signal associated with said 95 second line circuit at each station, and means at the central station for selecting and operating the signal of any station independently of said first aforesaid line circuit.

2. A system of the character described comprising a central station and a plurality of substations, two separate line circuits for uniting all of said stations, one line circuit to serve as a talking circuit and the other line circuit to serve as a signaling circuit; a telephone set at each substation for connection to the talking circuit; a selective signal-receiving device including a signal at each substation to notify the operator therat that he is wanted at the telephone associated 110 with the said station, and means at the central station to selectively operate either selective signal-receiving device and its associated signal independently of the talking circuit.

3. A system of the character described comprising a central station and a plurality of substations, a telephone set at each station, a line circuit uniting said stations, to which said telephones are adapted for connection, a second line circuit uniting all of said stations, means for connecting said telephones to said second line circuit, a selective signal-receiving device including a signal associated with said second line circuit at each station, and means at the central station for selecting and operating the signal of any station independently of said first aforesaid line circuit.

4. A system of the character described

comprising a central station and a plurality of substations, a telephone set at each station, a line circuit uniting said stations, to which said telephones are adapted for connection, a second line circuit uniting all of said stations, means for connecting said telephones to said second line circuit, means interposed in said second line circuit to limit telephone conversations between adjacent 10 stations, a selective signal-receiving device associated with said second line circuit at

each station, and means at the central station for selectively calling either station over said line circuit.

In witness whereof, I hereunto subscribe 15 my name this 1st day of February A. D., 1910.

HARRY O. RUGH.
